CLAIM

The ornamental design for a soap dispenser refill adapter, as shown and described.

DESCRIPTION

FIG. 1 is a top front perspective view of a soap dispenser refill adapter showing one embodiment of our new design; FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is an exploded top front perspective view of the soap dispenser refill adapter of FIG. 1, showing upper and lower adapter elements disconnected from one another.

FIG. 10 is a top front perspective view of the lower adapter element of the soap dispenser refill adapter of FIGS. 1 and 9;

FIG. 11 is a bottom rear perspective view of the lower adapter element of FIG. 10;

FIG. 12 is a front view thereof;

FIG. 13 is a rear view thereof;

FIG. 14 is a left side view thereof;

FIG. 15 is a right side view thereof;

FIG. 16 is a top view thereof; and

FIG. 17 is a bottom view thereof.

FIG. 18 is a top front perspective view of the upper adapter element of the soap dispenser refill adapter of FIGS. 1 and 9;

FIG. 19 is a bottom rear perspective view of the upper adapter element of FIG. 18;

FIG. 20 is a front view thereof;

FIG. 21 is a rear view thereof;

FIG. 22 is a left side view thereof;

(Continued)

FIG. 23 is a right side view thereof;
FIG. 24 is a top view thereof; and
FIG. 25 is a bottom view thereof.

FIG. 26 is a top front perspective view of a soap dispenser refill adapter showing a second embodiment of our new design;

FIG. 27 is a bottom rear perspective view thereof;

FIG. 28 is a front view thereof;

FIG. 29 is a rear view thereof;

FIG. 30 is a left side view thereof;

FIG. 31 is a right side view thereof;

FIG. 32 is a top view thereof;

FIG. 33 is a bottom view thereof; and

FIG. 34 is an exploded top front perspective view of the soap dispenser refill adapter of FIG. 26, showing upper and lower adapter elements disconnected from one another.

FIG. 35 is a top front perspective view of the lower adapter element of the soap dispenser refill adapter of FIGS. 26 and 34;

FIG. 36 is a bottom rear perspective view of the lower adapter element of FIG. 35;

FIG. 37 is a front view thereof;

FIG. 38 is a rear view thereof;

FIG. 39 is a left side view thereof;

FIG. 40 is a right side view thereof;

FIG. 41 is a top view thereof; and

FIG. 42 is a bottom view thereof.

FIG. 43 is a top front perspective view of the upper adapter element of the soap dispenser refill adapter of FIGS. 26 and 34;

FIG. 44 is a bottom rear perspective view of the upper adapter element of FIG. 43;

FIG. 45 is a front view thereof;

FIG. 46 is a rear view thereof;

FIG. 47 is a left side view thereof;

FIG. 48 is a right side view thereof;

FIG. 49 is a top view thereof; and,

FIG. 50 is a bottom view thereof.

The upper and lower adapter elements have been shown separately in FIGS. 10-25 and 35-50 to show aspects of the design that may not be apparent in the other views.
